UNITED STATES PATENT OFFICE

HARVEY J. LOUNSBURY, OF GLEN ELLYN, ILLINOIS, ASSIGNOR TO W. H. MINER, INC., OF CHICAGO, ILLINOIS, A CORPORATION OF DELAWARE

YOKE

Original application filed February 13, 1928, Serial No. 253,878. Divided and this application filed September 12, 1929. Serial No. 392,021.

This invention relates to improvements in yokes especially adapted for use in railway draft riggings.

This application is a division of my co-pending application Serial No. 253,878 filed February 13, 1928.

One object of the invention is to provide a yoke member especially adapted for railway draft riggings including the usual coupler and cooperating shock absorbing mechanism, wherein the yoke is provided with means for adequately supporting the coupler so as to maintain alinement thereof with the cooperating parts of the draft rigging and prevent drooping of the coupler head.

Another object of the invention is to provide a yoke of the character indicated, especially designed for railway draft riggings wherein the coupler has greater travel in buff than in draft.

A further object of the invention is to provide a yoke member having means for supporting the coupler shank of a coupler member of a railway draft rigging, so that the coupler shank parts inwardly of the point of support of the shank together with the connected yoke member overbalances the coupler head and shank portion outwardly of the support, thereby preventing drooping of the coupler head and maintaining the proper alinement of the coupler with the other parts of the draft rigging in all operative positions of the mechanism in both buff and draft.

Other objects of the invention will more clearly appear from the description and claim hereinafter following.

In the drawing, forming a part of this specification, Figure 1 is a longitudinal, vertical sectional view through the underframe structure of a railway car illustrating my improved yoke in connection therewith. Figure 2 is a plan view of the yoke proper, the forward end portion of the same being shown in the horizontal section. And Figure 3 is a vertical, transverse sectional view corresponding substantially to the line 3-3 of Figure 2. In said drawing, 10 indicates one of the draft sills of the car underframe structure, it being understood that two spaced draft sills are employed. The rear stop cast-

ing of the railway draft rigging is indicated by 11, the same being in the form of the usual filler casting located at the body bolster of the car. This casting has top and bottom arms 12-12, the front end faces of which form the stop members proper. The two stop arms 12-12 are so spaced vertically as to provide a combined guide and support for the rear end of my improved horizontal yoke indicated generally by the reference character A. At the end of the car, the sills 10 are provided with the usual slots for the coupler key 14. The front stops of the draft rigging are provided by an upper casting B and a lower casting C riveted to the sills. Said upper casting B has a front vertical end wall 17 adapted to act as an end plate, a horizontal web 18, a second horizontal web 19 downwardly offset from the web 18, and a vertical web 20 constituting the upper stop proper, said web 20 being reinforced by a horizontal flange 21. The lower casting C comprises a horizontal bottom wall or web 22 and a vertically extending web 23 constituting the lower front stop proper, said web 23 being suitably reinforced by strengthening flanges 24.

In connection with the yoke A I employ a standard coupler D; a front follower E; a friction shock absorbing device indicated generally by the reference character F. The follower E and device F are suitably supported in operative position by detachable saddle plates 25-25.

The yoke A is of the horizontal type, as before mentioned, the side members 26-26 thereof being integrally united at their front ends by a box-like section having side walls 27-27, a bottom wall 28 and a top wall 29. The box-like section forms the head member of the yoke which is adapted to accommodate the coupler shank. The side walls 27 are suitably thickened, as indicated in Figure 2, to provide the necessary bearing for the coupler key 14 and the inner surfaces of said walls are outwardly flared as indicated at 127, to permit lateral motion of the coupler D. The top and bottom walls 29 and 28 are disposed at the outer end of the yoke and extend to points substantially in line with the usual

horn of the coupler, the top wall 29 having a vertically extending flange 30 and the bottom wall 28 a depending flange 31. The upper flange 30 normally bears against the horn of the coupler and is adapted to engage the buffer plate 17 upon extreme buff movement. The side walls 27 are extended downwardly on each side of the yoke by means of vertical flanges 32-32, the lower edges of the latter 10 riding upon and being supported by the lower wall 22 of the stop casting C. In this manner, the horizontal yoke is supported in proper horizontal position at its front end and the necessary alinement of the coupler 15 shank with the axis of the shock absorbing device is maintained. The wall 28 forms a supporting shelf for the coupler shank, at such a point that the shank portion rearwardly of the front end of the shelf together with the 20 yoke connected thereto overbalances the weight of the coupler head. It will further be observed that in all operative positions of the parts there is no possibility of the coupler drooping or being tilted upwardly, inasmuch as the yoke A and the coupler are at all 25 times maintained in their alined position.

The friction shock absorbing device F, as shown, comprises a rectangular combined friction shell and spring cage casting 33 with 30 in which is contained the usual main spring resistance, not shown. As shown, the friction shell has friction shoes 35-35 cooperatin- 35 g therewith and a pressure-transmitting wedge 36 cooperates with the shoes.

Referring to the front follower E, the same is of heavy, thick formation and is provided with a central opening through which the pressure-transmitting member 40 extends and is freely movable, the pressure-trans- 40 mitting member being interposed between the inner end of the coupler shank and the front end of the wedge 36. The opening of the follower E is of smaller cross sectional area than the wedge block, so that outward 45 movement of the latter will be limited by engagement with the inner face of said follower.

In a buff action, the friction shell 33 is held 50 stationary by the rear stops 12-12. As the coupler moves inwardly, the pressure-trans- 55 mitting member or plunger 40 moves simultane- 60 ously therewith and directly actuates the wedge 36 of the friction gear, thus obtaining a compression stroke of the gear correspond- 65 ing to the inward movement of the coupler. In draft, outward movement of the coupler D causes a simultaneous movement of the yoke A and the latter in turn moves the shell 33 forwardly. During this draft action, the 70 wedge 36 of the friction device bears against the then stationary front follower E and con- 75sequently the friction device is actuated, as will be understood. The draft action continues until the shell 33 comes into engage- 80 ment with the follower E and this stroke will

preferably be limited to less than the buffing stroke.

I have herein shown and described what I now consider the preferred manner of carrying out my invention, but the same is merely 10 illustrative and I contemplate all changes and modifications that come within the scope of the claim appended hereto.

I claim:

As an article of manufacture, a yoke hav- 15 ing horizontally disposed spaced side arms connected at their inner ends and enlarged vertically at their forward ends, said enlarged portions of the arms being connected by horizontally disposed spaced top and bottom webs, said webs together with said enlarged portions of the arms defining a box-like hood adapted to accommodate the shank of a coupler, said bottom web being spaced above the bottom edges of said enlarged portions and providing a support for the coupler shank, 20 said arms having aligned coupler key slots rearwardly of said bottom web, the sections of said enlarged portions projecting below said bottom web having straight horizontal bottom guide edges adapted to cooperate with a carry iron or the like to slidingly support the yoke for maintaining the bottom web of said box-like section at standard coupler 25 height.

In witness that I claim the foregoing I have hereunto subscribed my name this 10th day of September, 1929.

HARVEY J. LOUNSBURY.
